UNITED STATES PATENT OFFICE.

HOLBERRY MENSFORTH, OF MANCHESTER, ENGLAND, ASSIGNOR TO THE BRITISH WESTINGHOUSE ELECTRIC & MANUFACTURING COMPANY, LIMITED, OF LONDON, ENGLAND.

CONDENSING APPARATUS.

1,229,636.

Specification of Letters Patent. Patented June 12, 1917.

Application filed June 26, 1915. Serial No. 36,538.

To all whom it may concern:

Be it known that I, HOLBERRY MENSFORTH, a subject of the King of Great Britain, and a resident of Manchester, England, 5 have made a new and useful Invention in Condensing Apparatus, of which the following is a specification.

This invention relates to condensing apparatus and particularly to steam condensers of the surface type.

Owing to various causes it is necessary that the tubes of surface condensers, through which the circulating water flows, should be cleaned from time to time in 15 order that the transference of heat from the steam in the condenser to the circulating water may not be unduly impeded and the efficiency of the condenser thereby impaired.

Various suggestions have from time to time been proposed for enabling portions of a surface condenser to be disconnected and cleaned or repaired without throwing 20 out of service the whole condenser, and to this end condensers divided up into separate compartments, having separate inlet and outlet valves for controlling the circulating water, have been suggested.

According to the present invention I construct two separate condensers, each of 30 which is substantially semi-cylindrical in shape, the two condensers being installed with their diametric plane faces in juxtaposition. A common exhaust pipe from 35 one or more steam engines, turbines, or the like, may lead to the two condensers, the exhaust pipe being branched before reaching the steam inlet of each condenser. Similarly the pipes leading from the discharge orifices for the condensate may converge 40 into a single pipe leading to the extraction pump. The two branches of the steam inlet pipe may or may not be provided with valves, as may be found most 45 desirable, but the outlet pipes leading from the condensate discharge ports should each have shut-off valves in those cases where said pipes converge into a single 50 outlet pipe or lead to the same extraction pump. A separate off-take for air and non-condensable gases is provided for each condenser and these may also lead to the same air pump, in which case each off-take must be furnished with a shut-off valve.

The invention is illustrated in the accompanying drawings in which Figure 1 is an end elevation of a condensing apparatus constructed in accordance therewith, the water box being removed, while Fig. 2 is a cross-section of the apparatus shown in Fig. 1, 55 illustrating two methods of staying the plane faces of the condenser shells. Fig. 3 is a cross section of the apparatus shown in Fig. 1, illustrating the construction of the sagging plate hereinafter referred to. Fig. 60 4 is a fragmentary longitudinal sectional elevation of the condenser shown in Fig. 1, taken on the line A—A of Fig. 3 looking in the direction of the arrow; and Fig. 5 is a fragmentary sectional view taken on the line 65 B—B of Fig. 3 looking in the direction of the arrow.

In Fig. 1 the two semi-cylindrical condensers are indicated at 1, 1^a installed as shown with their diametric plane faces in 70 juxtaposition. Each condenser is respectively provided with a steam inlet 2, 2^a, which are united into a common steam main 3 leading to the turbine or other engine, to which the condensers are to be connected. 75 4, 4^a indicate shut-off valves which may be provided, if desired, in the two branches of the steam main leading to the steam inlets of the condensers.

The condensate discharge pipes are indicated at 5, 5^a respectively, and are here shown as converging into a single outlet pipe 6 leading to the extraction pump. Shut-off valves 8, 8^a are provided in the pipes leading from the discharge pipes ahead of 90 the point where they converge into the common outlet 6. The air suction pipes of the two condensers are indicated at 7, 7^a. If these lead to the same air pump each air pipe must be provided with a shut-off valve. 95 The tube plates of the two condensers are indicated respectively at 9, 9^a. In addition suitable valves are provided for shutting off the circulating water to either of the condensers.

Condensers constructed as described with reference to Fig. 1 occupy approximately the same space as a single cylindrical condenser of equal capacity and possess the advantage that by closing the valves 4 and 100 8, or the valves 4^a and 8^a the appropriate valves in the water circulating system and if necessary the valve in the air suction

pipe 7 or 7^a either one of the condensers 1 or 1^a may be cut out of service for the purpose of inspection and cleaning or repair leaving the other condenser in operation, and thus the necessity for shutting down the engine or turbine or, in the alternative, providing an additional stand-by condenser is avoided.

Fig. 3 shows the plane portion 10 of the shell of the condenser 1 as being stayed by means of a sagging plate 11 secured in position by fitting bolts 12 to lugs 13 cast on the interior of the condenser shell 1. A sufficient number of sagging plates may be used to render any other support for the plane portion 10 of the shell unnecessary.

The right-hand portion of Fig. 2 shows an alternative method of staying the plane portion 10^a of the condenser shell 1^a. In this construction a horizontal web 14 is cast integral with and extends across the condenser shell, said web having openings 15 provided therein to allow the steam to pass from the upper to the lower portion of the steam space within the condenser. Alternatively, the web 14 instead of being cast integrally with the condenser shell may be made separate therefrom and secured thereto by any suitable means, such, for instance, as lugs and fitting bolts in a similar manner to that in which the sagging plates 11 are held in position.

An advantage resulting from the use of condensers constructed in accordance with this invention is that the tube plates are relatively cheaper to make owing to the width of the tube plates being small. The cost of the tube plates per pound weight increases with their width and for cylindrical condensers of large size are very expensive.

A further advantage resides in the fact that the size of the casting for the condenser shell is very much reduced, making it much easier to transport. Also, in the event of a defective casting the loss due to this cause is considerably diminished. These advantages are very perceptible in connection with condensers of large size the weight of which is considerable and the cost of transportation very heavy.

The invention is not limited to the precise details of construction described and illus-

trated herein, as various modifications may be made in the same without departing from the scope of the invention. For example, 55 the air suction outlets 7, 7^a may be omitted in those cases in which a wet air pump is used. Also, each of the condensers may be provided with its own extraction pump, in which case the condensate discharge pipes 60 will not converge into a common outlet pipe and the shut-off valves in the pipes leading from said pipes may be omitted. It will also be understood that the circulating water system of the condensers may be arranged in any convenient and well known way.

Having now particularly described and ascertained the nature of my said invention and in what manner the same is to be 70 performed, I declare that what I claim is:

1. Steam condensing apparatus comprising two separate cylindrical condensers having their diametric plane faces in juxtaposition, a steam inlet for each condenser, 75 branched from a common steam main, and a separate condensate discharge pipe for each condenser.

2. A condenser having a semi-cylindrical shell, tubes running longitudinally thereof, 80 and a stay for the flat lateral wall of the condenser shell extending across the interior of the condenser and at right angles to the tubes.

3. A condenser having a semi-cylindrical 85 shell, a stay for the flat wall of the shell, located within the condenser between the flat wall and the cylindrical wall thereof and extending transversely across the condenser at an angle to the axis of the condenser.

4. A condenser having a semi-cylindrical shell, a stay for the flat wall of the shell, located within the condenser between the flat wall and the cylindrical wall of the 95 condenser.

In testimony whereof, I have hereunto subscribed my name this 15th day of June, 1915.

HOLBERRY MENSFORTH.
